US0D1109042S

(12) **United States Design Patent** (10) Patent No.: **US D1,109,042 S**
(45) Date of Patent: ** Jan. 13, 2026

(54) **FLOOR MAT**

(71) Applicant: **Volvo Truck Corporation**, Gothenburg (SE)

(72) Inventors: **Vincent Lokers**, Summerfield, NC (US); **Ivan Palacios Rey**, Greensboro, NC (US); **Thomas Deboves**, Ecorse, MI (US)

(73) Assignee: **Volvo Truck Corporation**, Gothenburg (SE)

(**) Term: **15 Years**

(21) Appl. No.: **29/964,884**

(22) Filed: **Sep. 25, 2024**

(51) LOC (15) Cl. **12-16**

(52) U.S. Cl.

USPC **D12/203**

(58) **Field of Classification Search**

USPC D12/203, 221; D6/582-586, 592-594

CPC B60N 3/04; B60N 3/044; B60R 13/01
